US00D774215S

(12) **United States Design Patent** (10) **Patent No.:** **US D774,215 S**
(45) **Date of Patent:** ** *Dec. 13, 2016

(54) **SHINGLE**

(71) Applicant: **Building Materials Investment Corporation**, Dallas, TX (US)

(72) Inventors: **Luis Duque**, Hackensack, NJ (US); **Ming-Liang Shiao**, Collegeville, PA (US); **Sudhir Railkar**, Wayne, NJ (US)

(73) Assignee: **Building Materials Investment Corporation**, Dallas, TX (US)

(*) Notice: This patent is subject to a terminal disclaimer.

(**) Term: **14 Years**

(21) Appl. No.: **29/509,889**

(22) Filed: **Nov. 21, 2014**

(51) LOC (10) Cl. **25-01**

(52) U.S. Cl.

USPC **D25/139**

(57) **CLAIM**

The ornamental design for a shingle, as shown and described.

DESCRIPTION

FIG. 1 is a top plan view of our design for a shingle.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a perspective view thereof.

FIG. 7 is a bottom plan view thereof.

FIG. 8 is top plan view of a second embodiment of our design for a shingle.

FIG. 9 is a front elevation view thereof.

FIG. 10 is a left side elevation view thereof.

FIG. 11 is a right side elevation view thereof.

FIG. 12 is a perspective view thereof; and,

FIG. 13 is a bottom plan view thereof.
